UNITED STATES PATENT OFFICE.

PHILIP WUEST, JR., OF CHELTENHAM, PENNSYLVANIA, ASSIGNOR TO THE AUTO-MANUAL PIANO ACTION COMPANY, OF PHILADELPHIA, PENNSYLVANIA, A CORPORATION OF NEW JERSEY.

AUTOMATIC PLAYING MECHANISM FOR MUSICAL INSTRUMENTS.

No. 851,470.

Specification of Letters Patent.

Patented April 23, 1907.

Application filed March 18, 1905. Serial No. 260,703.

To all whom it may concern:

Be it known that I, PHILIP WUEST, Jr., of Cheltenham, in the State of Pennsylvania, have invented certain new and useful Improvements in Automatic Playing Mechanism for Musical Instruments, whereof the following is a specification, reference being had to the accompanying drawings.

My invention may be employed with particular advantage in pianos organs and similar instruments comprising automatic playing mechanism permanently adjusted in operative relation with their sounding devices; for instance, mechanism of the kind comprising a series of pneumatic motors or strike pneumatics respectively in operative relation to the individual sounding devices and having individual valve mechanisms controlled by a web of perforated paper which is progressed with respect to a pneumatic tracker bar provided with a series of apertures corresponding with a series of sounding devices in the instrument.

My improvements relate particularly to what may be termed the blowing mechanism by which the proper air pressure or degree of vacuum is maintained to operate said automatic playing mechanism. Ordinarily such mechanism comprises a single main chest or bellows having conduits leading respectively to a pneumatic motor by which the paper web is progressed and to the valve mechanism controlled by said web.

It is an object of my invention to reduce the bulk of the blowing mechanism so as to permit of its inclusion in a piano casing of ordinary dimensions, and to permit the maintenance of the proper degree of air tension in the apparatus by the minimum amount of labor, and, to this end I dispense with said ordinary main wind chest and employ in lieu thereof a wind chest having divisional compartments or bellows which are independently operative and become effective successively during the progress of the pumping operation. The effect of said arrangement is that the proper degree of air tension may be attained at the beginning of the pumping operation by the disturbance of the static condition of a single divisional compartment of the chest and before the static condition of any other division is disturbed,

but, said divisions are so co-related that during the continued operation of said playing mechanism they supplement each other to afford the maximum capacity required.

A convenient adjunctive feature of the general arrangement aforesaid is the provision of pneumatic means to control the ports by which communication is established between the divisions of the wind chest and the devices operated thereby, such means comprising a manually operative controlling valve conveniently disposed adjacent to the key board of the instrument, and, automatically operative diaphragm valves, thereby controlled, respectively local to the wind chest.

It may be noted that, one of the advantages of the divisional arrangement of the wind chest, hereinafter described, is that all of the divisions or bellows compartments of the chest are mounted upon the same side of a supporting panel, so as to afford the maximum capacity in the minimum amount of space in the instrument casing.

My invention comprises the various novel features of construction and arrangement hereinafter more definitely specified.

In the accompanying drawings, Figure I, is a vertical sectional view of a piano embodying my improvements, taken on the line I, I, in Figs. II, and III. Fig. II, is a fragmentary front elevation of the piano shown in Fig. I. Fig. III, is a plan sectional view of the blowing mechanism, taken on the line III, III, in Fig. I.

In said drawings, the piano casing 1, comprises the key frame 2, on which the digitals 3, are supported by the balance rail 4. Each of said digitals 3, is provided with an adjustable stud 5, and means operatively connecting it with a piano action, which may be of any convenient construction arranged to strike the string 11, on the metallic string frame 12, which latter is provided with the usual wooden back supports 13, and the sounding board 15. Said casing 1, also comprises the usual upper lid 17, the removable front panel 18, enclosing the action, the hinged cover 20, for the manual comprising the digitals 3, and, the removable front panel 21, enclosing the chamber 22, below the key frame 2. Said chamber 22, is provided with

the floor 23, which supports the panel 25, having the brackets 28, resting upon the floor, in removable relation. The two pumping bellows 30, are directly attached to said panel 25, as shown in Fig. III, and comprise the stationary frames 31, directly secured to said panel and the oscillatory leaves 32, which are hinged at their upper edges to said frames 31, and enclosed by flexible covers 33. Said leaves 32, have the air ports 35, provided with the diaphragm valves 36, which are secured, (conveniently by tacks 37,) at one end, and are provided at their opposite ends with blocks 39, to engage springs 40, which both maintain said diaphragm valves 36, in contact with said leaves 32, and strain them in the direction of their length. Said bellows 30, enclose the air ports 42, which extend through said panel 25, and are provided with the diaphragm valves 43, each secured at one end to said panel, (conveniently by tacks 44), and are provided at their opposite ends with the blocks 45, engaged with the springs 46, which both maintain said diaphragm valves 43, in contact with said panel 25, and strain them in the direction of their length. The leaves 32, of said bellows 30, being provided with the brackets 49, connected by the pivots 50, links 51, and pivots 52, with the pump pedals 54, said bellows 30, are thereby conveniently operated to alternately open and close said ports 35, and 42, thereby exhaust the air through said ports and create a partial vacuum within the chest with which said bellows are connected. Said pedals 54, are supported by pivots 56, on the frame 57, which in the operative position shown in the drawing has its feet 59, resting on the floor. However, said frame 57, is pivoted on the brackets 28, so that said frame and pedals may be upturned within said casing 1, through the doorway indicated by the dotted line in Fig. II, which may be closed by suitable doors indicated at 63, in Fig. I.

As best shown in Fig. III, the ports 42, open into the wind trunk 65, which thus connects the two pumping bellows 30, and, said trunk is provided at its opposite ends with the ports 66, and 67, respectively leading to the two reservoirs 68, and 69, being respectively in the pressure regulating bellows 74, and 75, comprising the stationary leaves 76, and 77, and the leaves 78, and 79, respectively hinged thereto. The reservoirs 68, and 69, as used in the present invention, are exhaust reservoirs, although it is obvious that they may be used as pressure reservoirs whenever the device is connected to a pressure operated instrument. Said bellows 74, and 75, are respectively provided with flexible covers 81, and 82, and the springs 84, and 85, tending to distend said bellows.

It may be noted that said reservoir 68, is of greater area than the other reservoir 69, and the springs 84, and 85, are so propor-

tional that the bellows 74, collapses at about one-half the pressure required to collapse the other bellows 75. For instance, I find it convenient in practice to so construct and arrange them that the bellows 74, collapses when there is a difference of seven pounds between the internal and external pressure upon its movable leaf 78, but the bellows 75, requires a difference of fourteen pounds pressure upon its leaf 79, to collapse it. Said reservoir 68, in the bellows 74, is connected by the conduit 88, with the series of strike pneumatic valve mechanisms, and, the reservoir 69, is connected by the conduit 89, with the motor by which the paper web is caused to traverse the tracker bar.

The ports by which communication is established between the interior of said reservoirs 68, and 69, and their respective conduits 88, and 89, are respectively controlled by similar automatic valve mechanisms, one of which is shown in section in Fig. I, comprising a flexible diaphragm 91, secured at its edges surrounding the adjoining ports 92, and 93, in the chamber 94, which ports respectively communicate with the reservoir 68, in the bellows 74, and, said conduit 88. Exterior to said diaphragm 91, said chamber 94, is provided with the conduit 96, leading to the trunk 65, and comprising adjoining ports 97, in the valve block 98, conveniently mounted upon the key frame 2, as indicated in Fig. II. Said conduit 96, may be opened or closed by manipulating the slide valve 99, by its operating handle 100; communication being established through said conduit 96, when the valve is in the position shown in Fig. II, in which its recess 101, registers with both of said ports 97.

The ports leading from the reservoir 69, in the pressure regulating bellows 75, to the conduit 89, are provided with valve mechanism similar to that shown in section in Fig. I, as above described, and comprising a diaphragm 103, in the chamber 104, which latter is provided with the conduit 105, leading to the trunk 65, and comprising the adjoining ports 107, in the valve block 108, controlled by the slide valve 109, having the recess 110, and the operating handle 111.

Said mechanism operates as follows:—The leaves 32, of the pumping bellows 30, being oscillated by the pedals 54, the valves 43, are closed and the valves 36, opened as said leaves pass to the collapsed position of the bellows shown in Fig. III, and, when said bellows 30, are distended by the movement of said leaves 32, in the opposite direction, the valves 36, remain closed, the valves 43, are opened and air is exhausted from the interior of the wind trunk 65, and through the latter from the divisional reservoirs 68, and 69, in the respective bellows 74, and 75. During the continued operation of the pedals 54, the pressure or degree of vacuum within

said reservoirs 68, and 69, is maintained practically constant by reason of their respective springs 84, and 85, tending to distend them. The ports leading from the reservoirs 68, and 69, in the respective bellows 74, and 75, to the conduits 88, and 89, and through the latter to the series of strike pneumatic valve mechanisms and the motor respectively are controlled as follows:—It being desired to establish communication between the reservoir 68, in the bellows 74, and the valve mechanisms, through said conduit 88; the valve 99, is shifted to the position shown in Fig. II, so that the conduit 96, is opened and the chamber 94, exhausted by communication with the trunk 65; causing the diaphragm 91, to assume the position shown in Fig. I, in which the ports 92, and 93, are uncovered by said diaphragm 91. It being desired to terminate such communication by closing said ports 92, and 93; it is merely necessary to shift said valve 99, to a position in which its recess 101, ceases to register with the ports 97, in the valve block 98, so that said conduit 88, is closed and thereupon the atmospheric pressure opposed to the partial vacuum within the bellows 74, causes said diaphragm 91, to close said port 92.

It is to be understood that communication between the reservoir 69, (in the pressure regulating bellows 75,) and the pneumatic motor, through the conduit 89, is established and terminated in a manner similar to that above described with respect to the conduit 88; by manipulating the slide valve 109, by its handle 111.

Although I have shown the two valves 99, and 109, arranged to be independently operated by a single handle, or, a single valve may be coupled so as to be contemporaneously actuated by their respective handles 100, and 111, it is to be understood that said valves or slide block may be provided with suitable recesses to control the respective ports leading to the conduits 88, and 89.

It may be noted that as heretofore constructed blowing apparatus of the class herein contemplated has comprised pumping bellows, a main chest, and auxiliary reservoir bellows; said bellows being on respectively opposite sides of said chest which connects them. Such construction of course presents the triple thickness of the two sets of bellows and the chest interposed between them, from front to rear of the instrument, and necessitates the employment of a piano casing larger than an ordinary casing.

It is one of the advantages of the construction above described that the main chest being dispensed with and the wind trunk 65, employed to connect the chest bellows 74, and 75, and the pumping bellows 30; all of said bellows are conveniently arranged upon the same side of said wind trunk, so that the

entire structure is of double instead of triple thickness and can be conveniently made of considerably less dimensions than the blowing mechanisms of the prior art.

It is to be understood that I do not desire to limit myself to the precise details of construction and arrangement herein set forth, as it is obvious that various modifications may be made therein without departing from the essential features of my invention.

I claim:—

1. The combination with a plurality of pumping bellows; of a plurality of reservoir bellows operatively related to but separate and distinct from said pumping bellows; and means pneumatically connecting said bellows, all of said bellows being on the same side of said connecting means, substantially as set forth. 75

2. The combination with a plurality of pumping bellows; of a plurality of reservoir bellows operatively related to but separate and distinct from said pumping bellows; and a wind trunk connecting said bellows, all of said bellows being on the same side of said wind trunk, substantially as set forth. 85

3. The combination with two pumping bellows; of pump pedals respectively connected in operative relation with said bellows; two reservoir bellows respectively at opposite sides of said pump bellows; and, a wind trunk connecting said pump bellows and reservoir bellows, all of said bellows being on the same side of said wind trunk, substantially as set forth. 90

4. In blowing mechanism of the class described, the combination with a plurality of pump bellows; of a plurality of pressure regulating bellows; and a wind trunk common to said regulating bellows directly connecting said pump bellows with said regulating bellows, all of said bellows being on the same side of said wind trunk, substantially as set forth. 100

5. In blowing mechanism of the class described, the combination with a panel; of two pump bellows hinged to said panel; pump pedals hinged to said panel; means operatively connecting said pedals with said pump bellows; a wind trunk secured to said panel and having ports leading to the respective pump bellows; two pressure regulating bellows respectively secured to said trunk; all of said bellows being on the same side of said wind trunk; springs normally tending to distend said regulating bellows; a motor; means connecting one of said regulating bellows with said motor; a series of strike pneumatic valves; and means connecting the other of said regulating bellows with said series of strike pneumatic valves, substantially as set forth. 115

6. In blowing mechanism of the class described, the combination with a plurality of

pump bellows; of means arranged to independently operate said bellows; a wind trunk connecting said bellows; independent pressure regulating bellows operatively related to but separate and distinct from said pumping bellows, respectively connected to the opposite ends of said trunk, all of said bellows being on the same side of said wind trunk; means tending to normally open said pressure regulating bellows; a motor; strike pneumatic valve mechanism; conduits leading from the respective bellows to said motor and to said strike pneumatic valve mechanism; valves arranged to automatically control the ports leading from said bellows; pneumatic means for operating said valves, comprising conduits extending to said trunk;

and manually operated valves controlling said conduits, substantially as set forth.

7. In a blowing mechanism of the class described, the combination with a wind trunk; of reservoir bellows at each end of said wind trunk; and a plurality of pump bellows upon said wind trunk between said reservoir bellows, all of said bellows being on the same side of said wind trunk, substantially as set forth.

In testimony whereof, I have hereunto signed my name, at Philadelphia, Pennsylvania, this 16th day of March, 1905.

PHILIP WUEST, JR.
